UNITED STATES PATENT OFFICE.

ELBA KENNETH MABRY, OF HOLDENVILLE, OKLAHOMA, ASSIGNOR OF ONE-THIRD TO
JOHN W. GILLILLAND, OF HOLDENVILLE, OKLAHOMA.

COLLAR.

1,186,926.

Specification of Letters Patent. Patented June 13, 1916.

Application filed April 22, 1915. Serial No. 23,197.

To all whom it may concern:

Be it known that I, ELBA K. MABRY, a citizen of the United States, residing at Holdenville, in the county of Hughes and State 5 of Oklahoma, have invented certain new and useful Improvements in Collars, of which the following is a specification.

The primary object of this invention is to obviate the use of the back collar button 10 generally resorted to as means for securing the back of a collar to the back band of a shirt or like garment.

The invention aims to facilitate the fastening and the loosening of a collar at the 15 back, to provide for the free sliding of the tie in collars of the lay down or turn over type, to reinforce the back portion of the collar to prevent its wilting in warm weather and to materially assist the laundry 20 dry thereof and to provide a collar which may be instantly fastened or released by one movement when placing the same in position or removing it from about the neck.

With these and other objects in view, 25 which will readily appear as the nature of the invention is better understood, the same consists in the improved construction and novel arrangement and combination of parts which will be hereinafter fully described 30 and particularly claimed.

In the accompanying drawing has been 35 illustrated a simple and preferred form of the invention; it being, however, understood that no limitation is necessarily made to the precise structural details therein exhibited, but that changes, alterations and modifications within the scope of the invention as claimed may be resorted to when desired.

Referring to the drawing:—Fig. 1 is 40 a perspective view of a collar of lay down type embodying the invention; Fig. 2 is a section on the line 2--2 of Fig. 1; Fig. 3 is a perspective view of a modification.

Corresponding and like parts are referred 45 to in the following description and indicated in all the views of the drawing by the same reference characters.

The collar is of the type embodying a 50 plurality of layers or plies which are assembled and secured by stitching in the well known way.

In the preferred form of the invention a 55 piece constituting a reinforcement is placed between the plies or layers comprising the collar and is secured therein by the usual

stitching employed for attaching the several plies without requiring extra or additional stitching. In this connection it is to be understood that within the purview of the invention the tab may be provided and secured to the collar in any manner depending upon the style and make of the collar. The tab 1 is located at the back of the collar and at or near the lower edge thereof and extends upward along the inner face of the 60 collar so as to engage the neck band of the shirt or like part of a garment to which the collar is to be attached when in position. The neck band of the shirt is generally formed in the back with a pocket to receive 65 the back of a collar button. The present invention utilizes this pocket as means for receiving the tab 1 which is entered therein when placing the collar in position about the neck, such operation being practically 70 effected at one movement since the tab may be inserted in the pocket at the same time that the collar is placed in position about the neck. The tendency of a collar is to move upward, hence the tab is retained in 75 the pocket when the front of the collar is fastened to the shirt or other garment in any of the usual ways.

The outline of the tab 1 is unimportant so long as the tab projects upward along the 80 inner face of the collar and is disposed at or near the lower edge thereof. In the preferred construction, as shown most clearly in Figs. 1 and 2, the tab 1 forms part of a piece 2 which is interduced between the plies or layers of the collar and which is stitched 85 thereto along the upper and lower edges of the collar, as indicated at 3 and 4, the stitching 3 and 4 being the same as originally employed for stitching the several 90 plies or layers comprising the collar. The upper portion of the piece 2 projects so as to conform to the fold of the collar, thereby 95 reinforcing such fold and maintaining ample clearance for the free sliding movement of the tie. The upper folded edge portion of the piece 2 is indicated at 5 and comes between the folded portions of the collar, thereby spacing such parts in a manner to 100 prevent clamping of the tie so that the same may slide freely when forming the knot. The lower portion of the piece 2 projects beyond the lower edge of the band of the collar and is folded upon itself to extend upward along the inner face of the collar so as 105 110

to enter the pocket of the shirt band, or other garment. The piece 2 may be of any material, fabric being preferred, and serves to reinforce or stiffen the back portion of the 5 collar with the result that the operation of laundering is facilitated and the collar is stiffened so as to prevent its ready wilting or breaking down in warm weather.

In the modification shown in Fig. 3 a 10 spacing strip 7 is interposed between the lower edge portions of the tab 1 and collar and serves to maintain a space between the tab and collar to insure the ready engagement of the tab with the garment or its entrance into the pocket at the back of the 15 shirt band. The spacing strip 7 is secured to the tab and collar by the same line of stitching 8 serving as fastening means for joining the plies of the collar and attaching 20 the tab thereto. In the form shown in Fig. 3 the spacing strip 7 is disposed in the lower fold of the piece 2.

It will be understood from the foregoing that the invention may be readily adapted to 25 any make or style of collar without requiring extra stitching since the tab may be secured to the collar by means of the ordinary stitching required for securing the several plies or layers comprising the collar. It is 30 noted, furthermore, that the tab by reason of its disposition enables the collar to be placed in position and made secure at one movement since the tab may be introduced in the pocket of the shirt band or engaged

with the garment by the same operation or movement required to place the collar in position.

It is also obvious that the collar may be removed and detached at the back by the same movement necessary to disengage the collar from the neck of the wearer. It will thus be understood that the annoyance, inconvenience and several objections incident to buttoning a collar in the back are wholly 45 obviated by the present invention and, moreover, provision is had for the ready sliding of the tie when forming the knot since there is no button or like fastening projecting to engage the tie and interfere with its sliding.

Having thus described the invention, what 50 is claimed as new is:

A collar comprising plies which are stitched along their edges, a reinforcing piece inserted between the plies and secured therein by the lines of stitching, an end portion of such reinforcing piece projecting beyond the lower edge of the collar and folded 55 upon itself to form an attaching tab which extends along the inner face of the collar, the upper portion of the reinforcing piece 60 extending across the fold to space the parts of the collar to prevent binding of the tie.

In testimony whereof I affix my signature in presence of two witnesses.

ELBA KENNETH MARRY. [L. s.]
